ABSTRACT OF THE DISCLOSURE

A new particle track etching method is disclosed where-
in a smoother and more uniform track profile is obtained
by controlling the chemical concentrations of the reagents
and products so that the etching occurs at a uniform rate.
Specifically, the etchant is maintained saturated with etch
products throughout the entire etching procedure.

This invention relates to particle track etching methods
and in particular to an improved method whereby the
bore made by the etchant along the path of the particle
has a uniform profile as opposed to an irregular profile
obtained by present methods.

As is now well known, tracks left by atomic particles
in solids can be enlarged for study by the use of an etchant
solution. The enlarged bores made by the etchant solution,
while suitable for studies relative to such things as the
track length and direction, are not as suitable for such
uses as filter elements having ultra-small holes as those of
the present invention. This is because presently used etch-
ants cause the hole to have a non-uniform profile.

In view of the above, it is therefore an object of the
present invention to provide a particle track etching
method wherein the bore made by the etchant has a
uniform profile.

The foregoing object is achieved wherein the etchant
material, from the start of the etchant process to the
completion of that process, is a saturated solution; i.e.,
saturated with the etch product. It has been found that
as the etch product concentration is increased there is
an abrupt change in the etching rate at the solubility limit
of the etch products. By controlling the etching process
so that it takes place at the maximum rate over the entire
surface of the material being etched, a uniform profile is
obtained along the particle track.

A more complete understanding of the present invention
may be obtained by considering the following detailed
description in conjunction with the attached drawing in
which:

FIG. 1 illustrates the general etching process.

FIG. 2 is a plan view of a comparison of the etching
process according to the present invention and that of
the prior art.

FIG. 3 is a side view of a comparison of the etching
process according to the present invention and that of
the prior art.

FIG. 4 illustrates curves showing bulk etching rate as
a function of etch product concentration.

Referring to FIG. 1 there is shown a block of material
10 containing a particle track 11. The material 10 may
comprise any suitable dielectric material such as a plastic
film which, for example, may be Lexan polycarbonate
film. As a charged particle passes through film 10, it
leaves a track of damage 11.

Upon being subjected to an etching solution, the surface
of the film 10 is etched away together with region along
the track 11. The rate at which the surface of the film 10
is worn away is known as the general etching rate. The
rate at which the track is etched away is called the track
etching rate. To obtain a track upon etching, the track

2

etching rate must be larger than the general etching rate
and the ratio of these two determines the shape of the
bore left by the etching solution. The configuration of
film 10 after being subjected to the etching solution is
illustrated by dashed lines 12 and 13. The thickness of
the film 10 has been reduced to the point indicated by
line 13 and is determined by the general etching rate.
The enlarged track portion 12, which may be conical in
shape, has its height determined by the track etching rate.
The profile of the bore 12 is generally rather irregular
when etchants of the prior art are used. It has been dis-
covered that upon saturation of the etchant solution with
etch products, the rate of etching abruptly increases to a
maximum and remains at the level for as long as the etch-
ing solution remains saturated. Utilizing this method,
much of the irregularity of profile can be alleviated.

A comparison of the method of the prior art and that
of the present invention is illustrated in FIGS. 2 and 3.
As shown in FIGS. 2 and 3, the bore 15 resulting from
the etchings of the prior art has an irregular profile 14.

In accordance with the present invention in which the
etchant solution is presaturated with etch products,
the resulting etching takes place at a maximum and a
uniform rate resulting in a bore 17 of uniform profile 16.

FIG. 4 illustrates a set of curves showing the bulk
etching rate as a function of etch product concentration
for two different etchant temperatures, namely, 40° C.
and 55° C. An example of an etchant that may be used
for Lexan is a 6.25 N aqueous sodium hydroxide solution
containing a 0.05 percent Benax 2A1 surfactant or wetting
agent. Benax 2A1 is made by Dow Chemical Company.
As can be seen from FIG. 3, an etching solution at 40° C.
has a bulk etching rate of about 0.08 micron per hour
until the etch product solubility limit is reached, where-
upon the bulk etching rate abruptly changes to about 0.17
micron per hour. Similarly, the bulk etching rate with
a 55° C. etchant gradually increases until the etch product
solubility limit is reached whereupon it can abruptly in-
creases to a stable value. Thus, by utilizing an etchant
that is saturated with etch products, a smooth bore along
the particle track is obtained.

Having thus described the invention, it will be apparent
to those skilled in the art that modifications may be made
within the scope of the present invention. For example,
the method of the present invention may be used in other
areas in which materials are etched, as in the semiconductor
fabrication art.

What I claim as new and desire to secure by Letters
Patent of the United States is:

1. An etching method for etching a material with an
etching solution producing etch products comprising the
steps of:
presaturating said etching solution with said etch
products,
subjecting said material to be etched to said presaturated
etching solution, and
maintaining said etching solution saturated with said
etch products during the etching of said material.
2. A method for etching a material containing particle
tracks with an etching solution producing etch products
comprising the steps of:
presaturating said etching solution with said etch
products,
subjecting said material containing particle tracks to
said presaturated etching solution, and
maintaining said etching solution saturated with said
etch products during the etching of said material.
3. A process as set forth in claim 2 wherein said etching
solution comprises an aqueous hydroxide solution and a
surfactant, and said material containing particle tracks
comprises a polycarbonate film.

4. A particle track etching process comprising the steps of:

subjecting a material containing particle tracks to an etching solution, presaturated with etch products, and maintaining the rate of etching of said material at a predetermined level, whereby the etching of the material will produce a uniformly dimensioned etched particle track.

5. A particle track etching process as set forth in claim 4 wherein said predetermined level is the maximum etching rate.
